Patented Dec. 2, 1975

237,870

COMBINED AIRCRAFT ANNUNCIATOR WARNING LIGHT AND TEST PANEL

Louis D. Belloisy, Waterbury, and Donald P. Gover,
Woodbury, Conn., assignors to James Di Rienzo and
Louis D. Belloisy, fractional part interest to each

Filed Jan. 24, 1974, Ser. No. 436,143

Term of patent 7 years

Int. Cl. D10—05

U.S. Cl. D10—103

FIG. 1

FIG. 2

FIG. 5

FIG. 6

FIG. 1 is a front elevational view of a combined aircraft annunciator warning light and test panel embodying our new design;

FIG. 2 is a rear elevational view thereof;

FIG. 3 is a right side elevational view thereof;

FIG. 4 is a top plan view thereof;

FIG. 5 is a left side elevational view thereof; and

FIG. 6 is a bottom plan view thereof.

We claim:

The ornamental design for a combined aircraft annunciator warning light and test panel, substantially as shown.
